Des. 2553

Samuel Conkey, of New York, N. Y.

Letter Patent No. 2553 Dated July 10, 1866.

Design for a Statuette.

The schedule referred to in these Letters Patent and making part of the same

It all whom it may concern:

Be it known that I, Samuel Conkey, of the City, County and State of New York, have invented a new and original Design for a Statuette; and I do hereby declare that the following is a full, clear, and exact description of, which will enable others skilled in the art to make and use the same, reference being had to the accompanying drawing forming part of this specification:

The drawing consisting of only one figure represents a Statuette made according to my Design.

The Design shows a mounted soldier in a re-
sitting position leaning with his right side against the
trunk of a tree, his right arm being supported by the trunk of the tree, and the hand of that arm supporting his head. His left arm is brought forward in front, and he holds in the left hand a rifle pistol. His left leg, which is extended, is bare-
daged. He is clothed in a shirt and pantaloons, and his
left foot, which is the only one here exposed to view, has on it a
stocking and shoe. His cap hangs on the back part of the trunk
and on each of the trunks are seen fern and grass. His
belt and cartridge box are partially exposed to view between
his right thigh and the trunk, and a cartridge pistol is
thrust against the trunk. His right foreleg is bent and
concealed beneath the left.

DS. 2353

2

On the front of the pedestal which supports the figure are inscribed the words "In the Wilderness, together with two verses of poetry, which latter are not embraced in my Design.

This Design is intended to be emblematical of the battles in the Wilderness between the Union and rebel forces in the spring of 1864.

of claim as new, and deserve to be granted a Patent. The Design for a Statue is herein represented and described.

The above Specification of my invention is signed by me this 15th day of November 1865.
